S. W. Tyler,
Mower.

No. 19,318

Patented Jan 26, 1858

UNITED STATES PATENT OFFICE.

SAMUEL W. TYLER, OF GREENWICH, NEW YORK.

IMPROVEMENT IN HARVESTERS.

Specification forming part of Letters Patent No. 19,218, dated January 26, 1858.

To all whom it may concern:

Be it known that I, SAMUEL W. TYLER, of Greenwich, in the county of Washington and State of New York, have invented certain new and useful Improvements in Harvesting-Machines; and I do hereby declare that the following is a full and exact description thereof, reference being had to the accompanying drawings, making a part of this specification.

Figure 1 is a top view of my improved harvesting-machine; Fig. 2, a rear elevation of said machine; Fig. 3, a side elevation of the same; Fig. 4, a vertical section in the line *y* of Fig. 1; Fig. 5, a section in the line *x x* of Fig. 1; and Figs. 6, 7, 8, and 9 are views of detached portions of said machine.

Similar letters indicate like parts in each drawing.

The respective movements of my improved harvesting-machine are combined with an oblong rectangular frame, which may be composed of the side beams, *s* *s'*, the end beams, *t* *t'*, and the central transverse beam, *f*, properly united to each other.

The rear end of the frame of said machine rests upon the wheels *D* *D'*, and the front end of said frame is supported by the pilot-wheel *B*. The bearing-wheels *D* *D'* are placed on the axle *F*, and the pilot-wheel *B* is pivoted within the hound *j*, which is connected to the front end of the frame of the machine by means of the linchpin *l*.

The finger-bar *b* is jointed to the vertically-adjustable head-piece *a*, which works within suitable guiding-brackets, *o* *o*, secured to the side *s* of the frame of the machine. The cam-lever *m*, which is jointed to the said head-piece *a* and bears against the side *s* of the frame of the machine, enables the inner end of the finger-bar to be elevated or depressed at pleasure, thereby enabling the said finger-bar to be adjusted to any desired distance from the ground, and also enabling the inner end of said finger-bar, together with the pitman *g*, to be elevated above the reach of stones or other similar obstructions.

The actuating-wheel *A* is secured to the center of the axle *F*, and has a zigzag groove formed in its periphery, which enables it to

impart motion to the cutter-blade by means of the pendulous lever *e* and the pitman *g*, as represented in Fig. 5. The pendulous lever *e* is jointed to the standard *d*, which rises from its connection with the central beam, *f*, of the frame of the machine.

The foot of the standard *d* fits into a groove whose sides are formed by the cheeks *p* *p*, which are bolted to the aforesaid beam *f*, and the said foot of the standard *d* is also jointed to the horizontal lever *h*, which is placed immediately in front of the cross-beam *f*, and is jointed to a projection from said beam, as represented in Fig. 1.

A pivot projecting from the pendulous lever *e* carries a roller, *v*, which fits into the zigzag groove in the actuating-wheel *A*, and thereby enables motion to be imparted to said lever.

By taking hold of the lever *h*, or by pressing against it by the feet of the driver, the standard *d* may at a moment's notice be moved forward a sufficient distance to throw the cutter-blade out of gear with the actuating-wheel.

By elevating the inner end of the finger-bar *b* by means of its jointed head-piece *a*, operated by the cam-lever *m*, and then disconnecting the pendulous lever *e* from the actuating-wheel, the finger-bar may be thrown into a vertical position for the purpose of enabling the machine to be more readily transported from place to place.

The clevis *k* serves the purpose of connecting the tongue *n* to the pivoted hound *j*, the said clevis being perforated in such a manner that by the use of two bolts or their equivalents the said hound may be thrown into any desired degree of inclination with the tongue.

When the hound *j* and the tongue *n* are properly adjusted, or, in other words, when they are adjusted with especial reference to the lateral strain exerted by the leverage of the finger-bar upon the tongue, the inclination of the pilot-wheel to run in oblique direction will entirely overcome the said lateral strain exerted by the finger-bar and cause the machine to run with perfect steadiness.

What I claim as my invention, and desire to secure by Letters Patent, is—

The sliding head-piece *a*, to which the inner end of the finger-bar is hinged, in combination with the levers *h* and *m*, the movable standard *d*, the pendulous lever *e*, and driving-wheel *A*, when the said parts are arranged for joint operation in the manner and for the purposes set forth.

The above specification of my improvement in harvesting-machines signed this 14th day of November, 1857.

SAML. W. TYLER.
